Primary Examiner — Susan Moon Lee(74) *Attorney, Agent, or Firm* — RatnerPrestia(57) **CLAIM**

The ornamental design for a mini document camera scanner, as shown and described.

DESCRIPTION

The FIGURE is a front, right side perspective view of a mini document camera scanner, the opposite left side perspective view being a mirror image thereof.

The appearance of the undisclosed bottom and rear of the mini document camera scanner is not claimed.

Broken lines and portions contained within broken line are not claimed.
